CLAIM

The ornamental design for a bottle filling station, as shown and described.

DESCRIPTION

FIG. 1 is a perspective view of a bottle filling station;

FIG. 2 is a front view thereof;

FIG. 3 is a back view thereof;

FIG. 4 is a top view thereof;

FIG. 5 is a bottom view thereof;

FIG. 6 is a left view thereof; and,

FIG. 7 is a right view thereof.

In the drawings, the broken lines depict portions of the bottle filling station that form no part of the claimed design.

1 Claim, 7 Drawing Sheets
